UNITED STATES PATENT OFFICE.

DILLON E. MAPOTIER, OF LOUISVILLE, KENTUCKY.

DESIGN FOR A GLASS VESSEL.

SPECIFICATION forming part of Design No. 22,075, dated December 20, 1892.

Application filed March 7, 1892. Serial No. 424,090. Term of patent 14 years.

To all whom it may concern:

Be it known that I, DILLON E. MAPOTIER, of Louisville, in the county of Jefferson, in the State of Kentucky, have invented a new and useful Design for a Glass Vessel, of which the following, taken in connection with the accompanying drawings, is a full, clear, and exact description.

My design relates to a glass vessel in the form of a modern locomotive, and is fully illustrated in the annexed drawing wherein

Figure 1 is a side elevation of the design; Fig. 2 is a longitudinal vertical section of the same, and Fig. 3 is a front view of the design.

The leading feature of my design consists in the form of a vessel which is in the conventionalized shape of a modern locomotive, wherein as shown in the drawings (A) is the

boiler, (B) the cab; (C) the smoke-stack, and (C') the pilot which stand distinct each from the other, while the driving wheels, steam-cylinder &c are brought out in outline only.

Having described my design, what I claim is:

The design for a glass vessel, substantially as herein shown and described.

In testimony whereof I have hereunto signed my name, in the presence of two attesting witnesses, at Louisville, in the county of Jefferson, in the State of Kentucky, this 2d day of March, 1892.

DILLON E. MAPOTIER.

Witnesses:

FREDERICK H. GIBBS,
M. L. GIBBS.
